PANIC BOLT

Norman B. Hurd, Newington, Conn., assignor to
The American Hardware Corporation, New
Britain, Conn., a corporation of Connecticut

Application February 1, 1935; Serial No. 4,458

7 Claims. (Cl. 70—29)

This invention relates to new and useful improvements in locking mechanism and is of particular utility when embodied in a so-called "panic" door bolt or latch in which pressure against an operating member at the inner side of a door causes the bolt to be released so that the door may freely swing outwardly. There are occasions when it is desirable to have the bolt held retracted so that the door may be freely opened from the outside, and it is in connection with a mechanism whereby this end may be attained that the present invention relates.

In the accompanying drawing—

Fig. 1 is a vertical cross-section of a door with my improved mechanism associated therewith, the same being shown partly in section and partly in elevation;

Fig. 2 is a view of the inside of the lock detached from the door and with the cap removed;

Fig. 3 is a similar view showing the operating parts in different position and showing a portion of the cap.

1 represents a door, 2 a lock case, 3 a removable cap, and 4 a bolt. In this instance the bolt is in the form of a spring latch pivoted at 4'—4' in the face 5 of the lock. 6 represents the latch-tail suitably connected at its front end with the bolt 4 and provided at its rear end with a guide plate 7. The tail 6 of the bolt 4 is guided between two abutments 8—8. 9 is a coil spring around the tail 6 and bearing at its rear end against the usual washer 10 positioned in front of the abutments 8. The forward end of the spring bears toward the bolt 4 so as to project it into its locking position shown in Fig. 3. 11 is a bolt retracting roll-back pivoted at 12 in the lock case. 13 is the end of a manually operable bell crank lever 14 pivoted at 15, usually on the outside of the case 2 at the inside of the door. The lever end 13 projects through a slot in the case and engages the roll-back 11 in such a manner that when the free end of the lever 14 is pushed toward the door the roll-back 11 will be moved from the position indicated in Fig. 3 to that shown in Fig. 2 and, since the upper end of the lever 11 engages with the guide plate 7, the bolt 4 will be retracted to the position shown in Fig. 2. When pressure on the lever 14 is released, the bolt 4 will be projected ahead to the locking position shown in Fig. 3. Ordinarily, the free end of the lever 14 is provided with a bar which extends across the door. A cross-section of this bar is indicated at 16 (Fig. 1). In the event of an emergency such as occasioned by a fire, pressure against the bar 16 in the door opening direction retracts the bolt so

that the door may freely swing open. 17 represents conventionally a key operable lock, such as a cylinder lock for example, which is accessible at the outside of the door 1 for operation by a suitable key (not shown). 18 is a key-operated spindle which is connected with a roll-back hub 19 having an arm 20 by which the bolt 4 may be retracted when the spindle is turned in the proper direction. This arm 20 normally rests against the upper end of the roll-back 11 and hence when the spindle is turned in a clockwise direction, as viewed in Fig. 3, it swings the roll-back 11 in the bolt retracting direction and thus permits entry from the outside. 21 is a bolt dogging device mounted to oscillate on the roll-back hub 19. 23—24 are spaced lugs on the side of the dog 21. 25 is a short arm mounted on the hub 19 and projecting between the lugs 23—24. 26 is a friction spring suitably mounted in the case and arranged to stand at one side or the other of a hump 27 on the hub of the dog 21 to frictionally hold it in one or the other of its extreme positions, one being shown in Fig. 2 and the other in Fig. 3.

Operation.—When the parts stand as shown in Fig. 3, the latch-bolt 4 may be freely retracted from the outside by a key capable of turning the spindle 18. When the parts stand as in Fig. 3, the space between the lugs 23—24 is sufficient to permit the bolt to be retracted by a key before the short arm 25 will encounter the lug 23 on the dog 21. When it is desired to hold the bolt 4 in the retracted position shown in Fig. 2 to permit free entry, the bolt 4 is first repressed to the position shown in Fig. 2; then, by turning the key-controlled spindle 18 in a counter-clockwise direction, the arm 25 will engage lug 24 and cause the dog 21 to swing down in front of the plate 7 and thus block the advance of the bolt 4. The space between the lugs 23—24 is such that the spindle 18 and the short roll-back arm 25 may be restored to their normal position, without disturbing the dogging position of the device 21. This permits the key to be removed. So long as the parts shown remain in this position, the bolt 4 will be held retracted so that the door may be freely opened from the outside to permit anyone to enter. When it is desired to restore the parts to the locking position, a key may again be employed and the parts shifted to the position shown in Fig. 3 so that the bolt 4 may be projected by its spring to perform the locking function. At all times when the dog 21 is "off", as shown in Fig. 3, the bolt 4 may be retracted by

means of the lever 14 at the inner side of the door.

I claim:

- 5 1. In a panic door bolt, a case, a spring projected bolt, mechanism including means at the inner side of a door to cause the bolt to be retracted by pressure toward the door, an oscillating bolt dogging means, a key-controlled roll-back concentric with said dogging means and 10 operable from the outer side of the door and having one portion for retracting said bolt and another portion for operating said dogging means.
- 15 2. In a panic door bolt, a case, a spring projected bolt, mechanism including means at the inner side of a door to cause the bolt to be retracted by pressure toward the door, bolt dogging means, a key-controlled roll-back, operable from the outer side of the door and having 20 one arm for retracting said bolt and another arm for operating said dogging means, said dogging means comprising an oscillating member mounted concentrically with said roll-back.
- 25 3. In a panic door bolt, a case, a spring projected bolt, mechanism including means at the inner side of a door to cause the bolt to be retracted by pressure toward the door, bolt dogging means, a key-controlled roll-back operable from the outer side of the door and having one 30 arm for retracting said bolt and another arm for operating said dogging means, said dogging means comprising an oscillating member mounted concentrically with said roll-back, and two shoulders on said dog at opposite sides of the 35 last mentioned arm and spaced to permit a limited amount of free motion of said arm during operation of the key-controlled roll-back for bolt retracting purposes.
- 40 4. In a panic door bolt, a case, a spring projected bolt, a bolt retracting roll-back, a device on the indoor side of the case and cooperating with said roll-back to retract the bolt by pressure on said device toward the case, another bolt retracting roll-back, a spindle therefor key-controlled from the outdoor side of said case, a dog 45 for the bolt to hold it retracted, said dog being

mounted on the hub of the second mentioned roll-back to oscillate thereon, and an arm mounted on said second mentioned roll-back to operate said dog to shift it into and out of the bolt-dogging position.

5 5. In a panic door bolt, a case, a spring projected bolt, a bolt retracting roll-back, a device on the indoor side of the case and cooperating with said roll-back to retract the bolt by pressure on said device toward the case, another 10 bolt retracted roll-back, a spindle therefor key-controlled from the outdoor side of said case, a dog for the bolt to hold it retracted, said dog being mounted on the hub of the second mentioned roll-back to oscillate thereon, an arm 15 mounted on said second mentioned roll-back to operate said dog to shift it into and out of the bolt dogging position, said last mentioned arm having a limited amount of free movement relatively to one of the parts with which it is associated without affecting the position of said dog.

6. In a lock, a case, a spring projected latch bolt, a key-operable roll-back to retract said latch bolt, a latch dog mounted to have limited oscillation on the hub of said roll-back, an arm 25 on said roll-back and engageable with said dog to move it "on" or "off", said dog having a limited amount of free movement relatively to the parts with which it is associated to permit said roll-back to be moved to retract said latch when 30 the dog is "off".

7. In a door lock, a spring projected latch bolt, mechanism including means for retracting said bolt from the inner side of a door to which said lock is applied, a key-controlled roll-back operable from the outer side of such a door to retract said latch bolt, an oscillating dog mounted concentrically with said roll-back, and means associated with said roll-back and movable therewith and cooperating with said dog to hold said latch in its retracted position when said roll-back is turned in one direction and to shift said dog to another position to release said latch bolt when said roll-back is turned in an opposite direction.

NORMAN B. HURD.
